UNITED STATES PATENT OFFICE.

OSBORN P. LOOMIS AND HENRY W. COOLEY, OF LYNN, MASSACHUSETTS.

REGULATOR FOR DYNAMO-ELECTRIC MACHINES.

SPECIFICATION forming part of Letters Patent No. 337,776, dated March 9, 1886.

Application filed September 22, 1885. Serial No. 177,792. (No model.)

To all whom it may concern:

Be it known that we, OSBORN P. LOOMIS and HENRY W. COOLEY, citizens of the United States, and residents of Lynn, in the county 5 of Essex and State of Massachusetts, have invented certain new and useful Improvements in Regulators for Dynamo-Electric Generators, of which the following is a specification.

Our invention relates to the automatic regulation of dynamo electric generators.

It has for its object the regulation of the working-circuit by means of a variable resistance in a shunt to the armatures; and it consists in the application of principles subsequently set forth, and includes such novelty as is embraced by the claims at the end of this specification.

The drawing hereunto annexed is described below by letters of reference in so far as our 20 invention is concerned.

In the single figure, A is a dynamo-electric machine of any type, having armature and field-magnets C.

B is an electro-magnet in a shunt-circuit to 25 the armature, and provided with a pole-piece, D, at one end.

E is a back piece to the magnet B, and is bent into the shape shown—*i. e.*, having a single rectangular bend.

30 F is a lever-armature, shaped as nearly as possible as shown—*i. e.*, provided with a projection, f, opposite the pole-piece D, pivoted to one end of the piece E and to the piston-rod G of the dash-pot H, and having one end resting upon contact-points I, which are connected together by conductors J, of comparatively high resistance.

K is a shunt-circuit, above referred to, and passes not only through the magnet B, but also 40 through one or more of the contact-pieces I and lever-armature F, and l represents the main circuit, in which may be included arc lamps M, or other translating devices.

The object of the dash-pot H, pivoted to the 45 end of the piece E, as shown, is for the usual purpose of dash-pots.

The operation depends upon the principle that the short-circuiting or shunting the armature more or less produces a variation in

the working-circuit; also, when the working- 50 circuit in a shunt to the armature varies. Further, when the working-current varies, the magnet strength of the magnet B also varies. In other words, if more lamps are introduced more current flows through the shunting arrangement, so that the lever F is pulled to the right from the position shown in dotted lines, and more of the resistances J are thereby introduced. Consequently more current is 55 furnished to the main current as required. 60

We are aware that variable resistances have been introduced into a shunt around the field-magnets, and we therefore lay no 65 claim to such a disposition of the said variable resistance.

Having stated the object of our invention, having described it by reference to the accompanying drawings, having described its *modus operandi*, and observing that we do not confine ourselves to the exact proportions shown in 70 the drawing or to the exact operations mentioned, what we consider novel, and desire to claim as the invention secured to us by the hereinbefore in part recited Letters Patent, is—

1. In combination with the armature and field-magnets of a dynamo-electric generator, a variable resistance and electric automatic-operating mechanism therefor, both located 75 in a shunt-circuit to said armature, the lamps or other translating devices being in series 80 with said field-magnets, substantially as described.

2. In combination with a dynamo-electric generator, a regulator consisting of the combination of an armature, a shunt to the armature, an electro-magnet in said shunt and provided with a pole-piece at one end, a back piece, E, for said magnet, bent at right angles, a lever-armature, F, pivoted at one end of said 85 back piece, having a projection upon it opposite said pole-piece and pivoted to a piston of a dash-pot, which is pivoted to the other end of the above-named back piece, and a series of contact-pieces connected together by 90 conductors of high resistance arranged in an arc to the axis of rotation of the above-named pivoted armature, and one of said contact- 95

pieces being in electrical contact with said pivoted armature, the said contact-pieces, one or more, and said pivoted armature being in a shunt-circuit to the armature of the 5 dynamo-electric generator, substantially as described.

In testimony that we claim the foregoing as our invention we have signed our names, in

presence of two witnesses, this 7th day of September, 1885.

OSBORN P. LOOMIS.
HENRY W. COOLEY.

Witnesses:

EBEN F. P. SMITH,
WALTER F. FISHER.
